400)

Hand-drawn network diagram for T1Q:4. The diagram shows connections between an IDDF, a T1Q:4 unit, and two 305 units.

Legend:

- Horizontal line: Main connection
- Vertical line: Ground connection
- Diagonal line: Cross connection
- Wavy line: Fiber optic connection
- Box with three parallel lines: T1Q:4 unit
- Box with two parallel lines: 305 unit

Nodes and Labels:

- IDDF:** Located at the top left, connected to several horizontal lines.
- T1Q:4:** Located in the center, connected to the main horizontal lines and the 305 units.
- 305:** Two 305 units are located at the bottom, connected to the main horizontal lines.
- 365, 364, 361:** Labels for the top horizontal lines on the left.
- 310, 311, 312, 313:** Labels for the vertical lines on the left.
- 210, 211:** Labels for the vertical lines on the right.
- 311:** Label for the vertical line in the T1Q:4 unit.
- 309, 308:** Labels for the bottom horizontal lines on the left.
- 307, 306:** Labels for the bottom horizontal lines on the right.
- 310, 311:** Labels for the top horizontal lines on the right.
- 312, 313:** Labels for the vertical lines on the right.
- 314, 315:** Labels for the top horizontal lines at the top right.
- 100:** Label for the bottom horizontal line at the bottom right.
- 111, 112, 113, 114:** Labels for the bottom horizontal lines at the bottom right.
- 100:** Label for the bottom horizontal line at the bottom right.

UNITED STATES PATENT OFFICE.

MICHAEL SCHWARTZ, OF CHICAGO, ILLINOIS, ASSIGNOR TO AUTOMATIC ELECTRIC INC., OF CHICAGO, ILLINOIS, A CORPORATION OF DELAWARE.

AUTOMATIC TELEPHONE SYSTEM.

Application filed December 16, 1922, Serial No. 607,270. Renewed January 22, 1926.

- The present invention relates in general to automatic telephone systems, but more especially to multi-office automatic telephone systems; and the object of the invention is 5 to produce a new and improved "director", or registering, translating, and sending apparatus for controlling the automatic switches, and new and improved trunking arrangements controlled by said director.
- 10 The present invention may be considered an improvement on or a modification of the director systems disclosed in British patents: 193,964 (complete accepted March 1, 1923), 194,580 (complete accepted March 15, 1923), 200,484 (complete accepted Aug. 1, 1924), 194,427 (complete accepted March 15, 1923), which patents correspond, respectively, to the United States applications: Serial No. 538,551, filed Feb. 23, 1922, Serial 15 No. 547,866, filed March 29, 1922, Serial No. 573,175, filed July 6, 1922, Serial No. 598,239, filed Nov. 1, 1922.
- 15 In the said application, Serial No. 538,551, filed February 23, 1922, an apparatus of the above character is illustrated and described. The director shown in that application is common to a large number of subscribers and is adapted to be connected to a first selector trunk when such trunk is taken for 20 use by a calling subscriber, whereupon registering devices in the director respond to the impulses from the subscriber's calling device and record the various characters, letters or digits, constituting the called telephone number. As soon as the first three 25 characters, or letters are registered, a sending device is set in motion and transmits series of impulses in accordance with a code derived by translation from these letters.
- 30 The code impulses operate a series of selector switches to trunk the call to the desired office, and the sending device then transmits the registered digits in the called telephone number to the selected office without 35 translation to operate other selectors and a connector to complete the connection to the called line. Means is provided whereby the transmission of any series of impulses, except the first, is made contingent upon the 40 completion of the trunk hunting movement in the selector which responds to the preceding series of impulses.
- 45 In the said application, Serial No. 547,866, filed March 29, 1922, an apparatus of similar character is illustrated and described,

the principal feature of improvement being that the directors are divided into groups, and "director selectors" are inserted between the first selector trunks and the directors. This arrangement reduced the number of 50 different calls handled by each director to approximately one-tenth of the total number, whereas in the former system the director had to be capable of handling all calls. The construction of the second director was, therefore, much less complicated and its cost was correspondingly reduced. One saving in particular, which may be mentioned, was brought about by the use of only one two-motion Strowger switch per 55 director, instead of the nine which were formerly required. A second feature in connection with the second director was the elimination of the revertive control of the sending switch by means of which the starting of the sending switch to operate any selector was made contingent on the completion 60 of the trunk hunting movement of the preceding selector. Instead of the revertive control, a standard time interval of approximately one-third of a second was inserted 65 between successive series of impulses, this time interval being slightly longer than the maximum hunting time of a Strowger selector switch.

70 The director forming the subject-matter of the present invention resembles the one last referred to and operates according to the same general principles. For the sake of simplicity, the present invention is shown in connection with a multi-office telephone system, such as may be found in exchange areas of moderate size, where there will never be more than one hundred offices and, for this reason, the "director selectors" may 75 be eliminated. The director, as shown, as common to a large number of subscribers and is adapted to be seized by a "director selecting line switch" associated with a trunk, when such trunk is taken for use by a calling subscriber. It is to be understood that the invention is not limited to the specific structure shown, but is equally as applicable when applied to telephone systems of larger size.

80 According to the principal feature of improvement, director controlled "switching line switches" are inserted between the trunk equipment and the first selectors. In general, the function of the switching line switch is merely that of selecting an idle 85

90 95 100 105 110

first selector, after which the connection is set up by the director in the usual manner. In the special case represented by a connection to a called substation located within the same office as the calling substation, the director, as soon as the critical character has been received, will cause the associated switching line switch to release the first selector and at the same time select an idle local third selector in the originating office. The director is then released and becomes available to other director selecting line switches. The further operation of the dial at the calling substation serves to directly operate the switches in the local office, thus completing the connection to the called line. From the foregoing, it will be seen that the invention provides means whereby, on calls between stations in the same office, the connection may be trunked directly from a switching line switch to a local third selector, thus releasing the first selector previously seized, as a result of which this switch is made available for use in setting up other connections.

Referring to the drawings, Figs. 1 to 5, inclusive, are circuit diagrams of sufficient of the apparatus used in a complete director system to illustrate the preferred form of the invention; Fig. 1 being a circuit diagram of a first selector trunk, a switching line switch, and a director selecting line switch; Figs. 2 to 5, inclusive, being circuit diagrams of a complete director.

Figure 6 is a trunking diagram of the system which is shown in detail in Figs. 1 to 5, inclusive.

Figure 7 is a front view of the subscriber's calling device showing the numbering of the dial.

Figure 8 is a layout showing how sheets 1 to 5, inclusive, should be joined together.

It will be advisable first to consider the trunking layout, Fig. 6, as an understanding of this will assist in the explanation of the rest of the drawings. It may be stated at the outset that the illustration of the trunking is only fragmentary. Each office in the system is provided with first and second selectors for handling the interoffice trunking, and in any given office the trunk lines extending to the other offices are, in general, taken from the banks of the second selectors. Assuming that a group of interoffice trunk lines is taken for a second selector level, these trunk lines would extend by way of repeaters to incoming third selectors at the terminating office, and connections would be completed at that office by means of the incoming third selectors, fourth selectors, and connectors. An arrangement similar to this is shown diagrammatically in Fig. 6. The subscriber at substation A in Bryant office may set up a connection with the subscriber at substation A' in the Sunnyside office by

means of the primary and secondary line switches C and C², a director selecting line switch C³ and a director, which director is capable of registering the called number SUNnyside 2345 and operating the switching line switch C⁴, the first and second selectors E' and E² in the originating office, and the incoming third selector E³, the fourth selector E⁴, and the connector H' in the terminating office to complete the connection. 75

A connection from the subscriber at station A to the subscriber at station A' in the Bryant office, in an ordinary director system, would be established in the following manner: The subscriber at substation A may set up the connection by means of the primary and secondary line switches C and C², a director selecting line switch C³, and a director, which director is capable of registering the called number BRyant 2375 and, neglecting for the time being the switching line switch C⁴, operating the first and second selectors E' and E², the local third selector E³, the fourth selector E⁴, and the connector H' to complete the connection. The introduction of the switching line switch C⁴, together with certain improvements in the director, allow a connection of this kind to be switched directly from the banks of the switching line switch C⁴ to the local third selector E³. The switching takes place when the director receives that critical character which determines that the call is for a station in the originating office, and results in the release of the first selector E, thus making it available for use in establishing other connections. 100

In Fig. 6 a trunk is shown extending from the bank of the secondary rotary line switch C² to a switching line switch C⁴. A relay equipment, indicated by the reference character D, is included in the trunk which is normally open at this point. From the relay equipment D the incoming and outgoing sections of the trunk extend to the director selecting line switch C³. When the calling subscriber seizes the trunk line, the director selecting line switch C³ is operated to select an idle director. When this is accomplished, the incoming and outgoing sections of the trunk are extended to the selector-director. The director then causes the switching line switch C⁴ to select an idle first selector. The director is now in readiness to register the letters and digits of the called number, and to provide for the transmission of the required series of impulses by the director to operate the train of switches by means of which the connection is completed. 115

The apparatus in Figs. 1 to 5, inclusive, may now be explained more in detail. Fig. 1 shows the detailed circuit arrangements of the relay equipment D, switching line switch C⁴ and the first selector trunk which is 120

depicted in Fig. 6 together with the director selecting line switch C^3 . The trunk conductors 13, 14, and 15 extend from multiple sets of contacts in the banks of secondary 5 rotary line switches such as the line switch C^2 , one of which set of contacts is indicated by reference characters 10, 11, and 12, by way of the relay equipment D to the switching line switch C^4 . The relay equipment D comprises three relays, and the line conductors of the trunk are normally open at the contacts of one of these relays, both the incoming and outgoing sections of the trunk being indirectly extended to the director selecting line switch C^3 , which is located below the trunk relay equipment D. 10

The director selecting line switch C^3 is a step-by-step rotary switch of the type in which the wipers move in a forward direction only. In further explanation, it should be stated that this switch is of the type in which the wipers are advanced when the stepping magnet retracts its armature, rather than when the stepping magnet is energized. 15 The trunk conductors 172, 173, 174, and 175 extend from multiple sets of contacts in the banks of director selecting line switches such as the line switch C^3 , one of which set of contacts is indicated by the contacts 168, 169, 30 170, and 171, to the director indicated in Figs. 2, 3, 4, and 5.

The switching line switch C^4 is a step-by-step rotary switch of the type in which the wipers move in a forward direction only. 35 In this connection, it may be stated that this switch is of the type in which the wipers are advanced when the stepping magnet retracts its armature, rather than when the stepping magnet is energized. In further explanation, it should be stated that the stepping magnet operates a single shaft to which is mounted a primary set of wipers indicated by the reference numbers 75, 76 and 77 and a secondary set of wipers indicated by the reference numbers 117, 118, and 119, each set of wipers being designed to engage the contacts in an associated multiple bank. One set or the other of these wipers will be connected to the trunk conductors 47, 48, and 49 of the switching line switch C^4 , depending upon the energization or deenergization of relay 62. The trunk conductors 104, 105, and 106 extend from multiple sets of contacts in the primary banks of switching line switches such as the line switch C^4 , one of which set of contacts is indicated by reference characters 101, 102, and 103, to the first selector E' . The trunk conductors 123, 124, and 125 extend from multiple sets of contacts in the secondary banks of switching line switches such as the line switch C^4 , one of which set of contacts is indicated by reference characters 120, 121, and 122, to the local third selector E^6 . 60

The first selector E' and the local third

selector E^6 are vertical and rotary switches of the Strowger type, and each has access to 100 sets of contacts arranged in ten horizontal rows or levels. The circuit of these switches is a standard two-wire circuit of 70 well-known type and for that reason has been shown only in part.

One of the directors is shown complete in Figs. 2 to 5, inclusive, and comprises the master digit controller M, Fig. 2; the B and C impulses register J, Fig. 4; a thousands register M' , a hundreds register M^2 , a tens register M^3 , a units register M^4 , all of which are shown in Fig. 2; an impulse sending switch S, Fig. 3; a sequence switch S' , Fig. 5; and an intermediate distributing frame I. D. F., Fig. 4. 75

The master digit controller M and the four digit registers M' to M^4 , inclusive, are simple ten-point step-by-step switches, each of which are provided with an operating magnet, a release magnet, and a set of off normal springs which are operated when the switch wipers are advanced out of their normal position. 80

The B and C impulse register J is a Strowger switch of the vertical and rotary type having 100 sets of contacts arranged in ten horizontal rows or levels. The operating and release magnets of the switch J are controlled over conductors coming from the master digit controller M, Fig. 2, and, consequently, the switch requires no relays. Four wipers, indicated by the reference characters 306 to 309, inclusive, are shown to the right of the operating magnets in Fig. 4, which also shows the first five sets of contacts in the third level of the bank to which these wipers have access. All of the contact sets in the bank which correspond to working exchanges, of which correspond to exchanges which it is anticipated will be installed, are wired to terminal sets on the left-hand side of the I. D. F., as shown in the case of the second and fifth contact sets. 90

The right-hand side of the intermediate distributing frame consists of fifteen or more bus-bars, each having a plurality of terminals in order to provide facilities for cross-connecting any terminal on the left-hand side of the I. D. F. with any bus-bar. The first nine bus-bars correspond to the nine digits, 1 to 9, inclusive, and are so marked in the drawing. These bus-bars are connected in multiple with the banks of the register switches M' to M^4 , inclusive, and with the bank of the sending switch S, as is shown in Figs. 2 and 3. Bus-bars X, Y, and Z provide for automatically advancing the sequence switch S' on office codes which have less than the maximum number of series of impulses; bus-bar SW is a special switching bus-bar used to control the switching through at the trunk 100 105 110 115 120 125 130

equipment D when that critical character is reached which indicates that the called station is in the same office as the calling station.

- 5 The intermediate distributing frame represented diagrammatically in Fig. 4 is assumed to be of standard type, with standard terminal arrangements on one side, and having permanent cable connections between 10 the left-hand side and the bank of the B and C impulse register J, and permanent cable connections from the bus-bars on the right-hand side to the banks of the register and sending switches.
- 15 The sending switch S, Fig. 3, and the sequence switches S', Fig. 5, are step-by-step rotary switches of the type in which the wipers move in a forward direction only. In further explanation of these switches, it 20 should be stated that they are of the type in which the wipers are advanced when the stepping magnet retracts its armature, rather than when the stepping magnet is energized.
- 25 The general object and scope of the invention having been pointed out, the operation of the apparatus involved will now be described more in detail, and for this purpose it will be assumed that the subscriber at station A, Fig. 6, desires to establish 30 connection with the subscriber at station A', whose telephone number is SUNnyside 2345. When the receiver is removed at station A, the calling line is extended in a known manner to a trunk line such as the one extending to the trunk relay equipment D by means of the primary line switch C and a secondary line switch such as the secondary line switch C². Assuming that the secondary 35 line switch in use connects with the set of bank contacts indicated by reference characters 10, 11, and 12, Fig. 1, the two conductors of the calling line will be connected with trunk conductors 13 and 15, and a circuit will be completed over the said trunk conductors for the double wound line relay 23 of the trunk relay equipment D. Relay 23 is accordingly energized and at armature 25 closes a circuit for the slow-acting line relay 150 of the director selecting line switch C². On energizing, the latter relay connects 40 ground at armature 156 to the release trunk conductor 14, thereby completing a holding circuit for the operated line switches in the usual and well-known manner. A further result of the energization of relay 150 is the closing of a circuit for the switching relay 157 in series with the stepping magnet 162 at armature 151, and at armature 152 connects the test wiper 167 to the above circuit at a point between the winding of the switching relay and the winding of the stepping magnet. If the trunk with which the wipers of the director selecting line switch 45 50 55 60 65 70 75 80 85 90 95 100 105 110 115 120 125 130 C² are now associated is busy, there will be a ground on the test contact with which the test wiper 167 is in engagement, the switching relay 157 will be short circuited, and the stepping magnet 162 will be operated to advance the switch wipers into engagement with the next trunk line. If the next trunk line is busy, the same operation will be repeated and the stepping magnet 162 will continue to operate in the manner of a buzzer to advance the switch wipers step-by-step until an idle trunk line is encountered. However, if the trunk lines with which the wipers of the line switch are associated is idle, there will be no ground potential on the test contact engaged by the test wiper 167, and the switching relay 157 will not be short circuited, but will be immediately energized in series with the stepping magnet 162, the said magnet remaining inoperative due to the high resistance of the switching relay. Assuming that when the line relay is energized in the present case, the director associated with the set of bank contacts indicated by the reference numbers 168, 169, 170, and 171 is idle, then switching relay 157 will be immediately operated when its circuit is completed by the said line relay, as pointed out under the second alternative above.
- When the switching relay 157 pulls up, a considerable number of circuit changes are brought about. At armature 163 of relay 157 ground is connected through test wiper 167 to test contact 171 and its multiples in the banks of other director selecting line switches in order to make the selected director busy. Disregarding for a time the circuit changes introduced in the director, the operation of the switching line switch C⁴ will now be explained. When the switching relay 157 of the switch C³ was operated, a circuit was closed through relay 27 of relay equipment D, the circuit being traceable from ground at resting contact of armature 523, Fig. 3, conductor 174, bank contact 169, wiper 165, working contact and armature 159, winding of relay 27 to battery. Relay 27, upon energizing, closes a circuit for the line relay 61 of the switching line switch C⁴, the circuit being traced from ground by way of resting contact and armature 49, armature 35 and its resting contact, working contact and armature 26, resistance 6, resting contact and armature 36, armature 54 and resting contact, winding of line relay 61 to battery. On energizing, relay 61 closes a circuit for the switching relay 57 in series with the stepping magnet 68 at armatures 59 and 60, and at armature 64 connects the test wiper 76 to the above circuit at a point between the winding of the switching relay and the winding of the stepping magnet. If the trunk with which the primary wipers 75, 76, and 77 of the switch C⁴ are now associated is busy, there will be ground on the

test contact with which the test wiper 76 is in engagement, the switching relay 57 will be short circuited, and the stepping magnet 68 will be operated to advance the 5 switch wipers into engagement with the next trunk. If the next trunk line is busy, the same operation will be repeated and the stepping magnet 68 will continue to operate in the manner of a buzzer to advance the 10 switch wipers step by step until an idle trunk line is encountered. However, if the trunk line with which the wipers of the line switch are associated is idle, there will be no ground potential on the test contact engaged by the test wiper 76, and the switching relay 57 will not be short circuited, but will be immediately energized in series with the stepping magnet 68, the said magnet remaining inoperative due to the high resistance 15 of the switching relay. Assuming that when the line relay is energized in the present case, the first selector E' is idle, then switching relay 57 will be immediately operated when its circuit is completed by the 20 said line relay, as pointed out under the second alternative above. On attracting its armature 56, the switching relay disconnects the test wiper 76 from armature 64 of the line relay and connects it instead to its own 25 upper terminal, the ground potential which is thus placed upon the test contact 102 being effective to render the trunk line busy to other calls. In addition to the foregoing, relay 57 at armatures 54 and 49 disconnects 30 the line conductors 50 and 53 from the line relay 61 and ground, respectively, and extends them by way of armatures 69 and 71 of relay 62, wipers 75 and 77, bank contacts 101 and 103, conductors 104 and 106, and 35 armatures 135 and 136 of relay 137 to the upper and lower windings of the line relay 107 of the first selector E'.

When the trunk is extended to the line relay 107 as previously explained, this relay is 40 energized and at armature 138 closes a circuit for the slow-acting release relay 108. Upon energizing, relay 108 connects ground to the release trunk conductor 105 at armature 109, thereby closing a holding circuit 45 for the switching line switch C⁴, which extends by way of the said conductor 105, test contact 102, test wiper 76, resting contact and armature 70, armature 56 and its working contact, winding of the 50 switching relay 57, and the winding of the stepping magnet 68 to battery. This holding circuit is established before the slow-acting line relay 61 has had time to deenergize, and is effective to retain the line switch C⁴ in operated position throughout the 55 connection. It will be seen that the holding ground is extended to conductor 51 by the operation of armature 55.

Returning now to the circuit changes produced 60 in the director by the operation of

the switching relay 157 of the director selecting line switch C³, it may be said that ground potential is placed on holding conductor 172 and, since this conductor is connected by way of normally closed contacts at armatures 525 and 527, Fig. 3, it follows that relays 510 and 511, Fig. 3, will be energized. Relay 511, on energizing, removes ground from the upper bank of the sequence switch S' at armature 533, and at armature 70 532 disconnects wiper 513 of the sending switch S from the stepping magnet 515. Relay 510, on energizing, disconnects relay 509 at armatures 529 and 531, and at armature 530 removes ground from the release 75 conductor 204.

Another result of the energization of the switching relay 157 of the director selecting line switch C³, is the preparation of an impulsing or control circuit for the vertical magnet 303 of the B and C impulse register J, Fig. 4, which may be traced as follows: from ground at the resting contact of armature 24, Fig. 1, by way of the working contact of armature 160, wiper 166, bank contact 170, conductor 173, armature 538 and its resting contact, conductor 202, the winding of the low resistance slow-acting series relay 207, wiper 218 of the master digit controller M in first position, conductor 301, and the winding of the vertical magnet 303 to battery. The preparation of this circuit places the B and C impulse register J in condition to receive the first two 80 series of impulses from the calling line. 85

As a further result of the energization of the switching relay 157, the conductor 52 associated with the switching line switch C⁴ is extended at armature 158 to wiper 164 and is thus connected by way of bank contact 168 with conductor 175; this operation is without effect at this time. 90

When the calling subscriber operates his calling device for the first letter in the called number, or the letter S, three interruptions will be produced in his line circuit and the line relay 23 in the trunk relay group D will be deenergized three times. Accordingly, the line relay 23 will transmit a series of three impulses over the previously traced operating circuit to the vertical magnet 303 of the B and C impulse register J. In response to these impulses, the magnet 303 operates to raise the wipers 306 to 95 100 105 110 115 120 125 130 135 140 145 150 155 160 165 170 175 180 185 190 195 200 205 210 215 220 225 230 235 240 9995 9999

the circuit of relay 208, whereupon the latter relay deenergizes also. Since, relay 208 is slow-acting, however, it will not be deenergized until an instant after relay 207 has retracted its armature and a momentary impulse of current will be transmitted to the stepping magnet 212 of the master digit controller M from ground by way of armature 215 and its resting contact, armature 216 and its working contact, and the winding of the stepping magnet 212 to battery. By the operation of the stepping magnet 212, wipers 218 and 219 are advanced into second position.

15 When the calling subscriber dials the next letter in the called number, or the letter U, five interruptions will be produced in his line circuit, and the line relay 23 of the trunk relay group D will be deenergized 20 five times. This relay, accordingly, transmits five impulses of current over the previously traced operating circuit, and now, since the wiper 218 of the master digit controller M is standing in second position, 25 these circuit impulses will pass over conductor 302 and through the rotary magnet 304. By the resulting operation of the rotary magnet, wipers 306 to 309, inclusive, are advanced five steps in a rotary direction and are brought to rest in engagement with the fifth set of contacts in the third level.

During the rotary movement of the B and C impulse register J, the slow-acting series 35 relay 207 of the master digit controller M is energized the same as it was during the vertical movement, and completes a circuit for the slow-acting relay 208. At the end of the rotary movement, these two relays 40 deenergize an instant apart and thus cooperate in transmitting an impulse of current to the stepping magnet 212 of the master digit controller M, the wipers of which accordingly advance to third position. At wiper 45 218 the operating or control circuit coming from the director selecting line switch C over conductors 173 and 202 is shifted from the rotary magnet of the B and C impulse register J to the stepping magnet 227 of 50 the thousands register M', while at wiper 219 a ground is placed on starting conductor 400.

Responsive to the grounding of the start wire 400, the sending switch S begins to 55 transmit impulses in accordance with the office code which has been determined on by the dialling of the first three letters of the called number, but it is thought best to defer the explanation of these operations in order 60 to permit an explanation of the operation of the register switches M' to M⁴, inclusive, in registering the four digits of the called numbers. When the calling subscriber operates his calling device in accordance with 65 the digit 2 of the called number, the line

relay 23 of the trunk relay equipment D responds in the usual manner and transmits two impulses to the stepping magnet 227 of the thousands register M'. By the operation of the stepping magnet 227, wiper 244 is advanced two steps into engagement with the second contact in its associated bank. When the switch leaves its normal position, the off normal springs are shifted and spring 236, by engaging its working contact, prepares a circuit for grounding conductor 421 which is completed when the slow-acting series relay 231 deenergizes at the end of the series of impulses. Relay 231, it may be stated, is energized in series with the stepping magnet 227 and holds its armature 235 attracted during the stepping movement of the register switch in order to prevent the conductor 421 from being grounded until the registration of the digit is completed.

The slow-acting series relay 207 is also energized in series with the stepping magnet 227 and in conjunction with relay 208 operates to transmit another impulse of current to the stepping magnet 212 of the master digit controller at the proper time, whereby wipers 218 and 219 are advanced to the fourth position. Wiper 218, in shifting from third to fourth position, shifts the control circuit from the stepping magnet 227 of the register switch M' to the stepping magnet 226 of the hundreds register switch M². No circuit changes are brought about by the further movement of wiper 219, since contacts 3 to 10, inclusive, in the bank associated with this wiper are multiplied together. It may be stated that wiper 219 should preferably be so constructed that when advanced from contact to contact it will engage a new contact each time before it disengages the preceding one.

It will be unnecessary to describe in minute detail how the other three register switches M², M³, and M⁴ are operated responsive to the dialling of the remaining three digits of the number. It will be sufficient to point out briefly that when the hundreds digit 3 is dialled, the line relay 23 will transmit three impulses of current through relays 207 and 230, and through the stepping magnet 226 in series, whereby the said stepping magnet is operated to advance wiper 245 into engagement with the third contact in its bank. At the end of the stepping movement, relay 230, which holds up its armature 234 during the operation of the register switch, deenergizes and connects ground to conductor 422. At the same time, the slow-acting relays 207 and 208 transmit an impulse to the stepping magnet 212 of the master digit controller in order to advance the wipers 218 and 219 to fifth position. In a manner similar to the above, when the calling subscriber dials the tens digit 4 and the units digit 5, a series of four

impulses is first transmitted to the stepping magnet 225 of the tens register M^3 , and a series of five impulses is then transmitted to the stepping magnet 224 of the units register M^4 , it being understood, of course, that the control circuit is shifted from magnet 225 to magnet 224 at the proper time by wiper 218 of the master digit controller M . Wiper 246 of register switch M^3 is accordingly advanced into engagement with the fourth contact in its bank, while wiper 247 of the register switch M^4 is advanced into engagement with the fifth contact in its bank. Conductors 423 and 424 are grounded when the slow-acting relays 229 and 228 fall back after the completion of the operation of their respective associated register switches.

The operation of the sending switch S , Fig. 3, may now be taken up. As stated before, this switch begins operating to transmit impulses in accordance with the required office code as soon as the last of the two letters of the number has been dialled, the actual starting of the sending switch being accomplished by the grounding of the starting wire 400 when the wiper 219 of the master digit controller M arrives in third position. The code in accordance with which the call is trunked to the SUnnyside office is 63, as may be perceived from an inspection of the trunking diagram, Fig. 6, and accordingly, the fifth set of contacts in the third level of switch J , which set of contacts is selected by dialling the letters SU, is so cross-connected at the intermediate distributing frame as to cause the transmission of two series of impulses, the first series comprising six interruptions and the second series comprising three interruptions. More in detail, terminal 333 is cross-connected to bus-bar No. 6, terminal 332 is cross-connected to bus-bar No. 3, terminal 331 is cross-connected to bus-bar Y, and terminal 330 is cross-connected to bus-bar X. These cross-connections will cause the required series of impulses to be transmitted by the sending switch S , as will be understood shortly.

Conductor 400 extends to the sequence switch S' , Fig. 5, where it is connected to wiper 404 and to the first four contacts in the bank of wiper 405. Accordingly, when this conductor is grounded, a ground is placed in the No. 6 contact in the bank of the stop wiper 514 of the sending switch S , the circuit being traceable from the grounded conductor 400, by way of sequence switch wiper 404, in first or normal position, conductor 411, wiper 306 of register switch J and the contact now engaged thereby, terminal 333 on the left-hand side of the I. D. F., a jumper connecting this terminal with bus-bar No. 6, and thence by way of conductor 366 to the No. 6 contact in the

bank of stop wiper 514 of the sending switch. At the same time that the above circuit is completed, a circuit is completed for the impulsing relay 507 of the sending switch over the following path: from the grounded conductor 400 by way of wiper 405 in first position, conductor 425, resting contact of armature 519 and the said armature, resting contact of armature 540 and the said armature, winding of the impulsing relay 507, and through the interrupter I to battery. The interrupter I is continuously driven and consists of any suitable cam arrangement for intermittently connecting battery to the relays such as relay 507 at the rate of about ten times per second. When this circuit is closed, therefore, or shortly afterwards, depending upon the position of the interrupter I, relay 507 is energized and opens the impulsing contact at armature 523, this operation being of no effect, however, due to the fact that the contact at armature 523 is short-circuited at armature 520 of relay 506. Relay 507 also closes the circuit of stepping magnet 515 at armature 524, and the said magnet is energized. When the circuit of relay 507 is broken by the interrupter I an instant later, the relay falls back and again closes its impulsing contact at armature 523, and breaks the circuit of the stepping magnet 515, which thereupon retracts its armature and advances the wipers 513 and 514 one step. A circuit is now completed for relay 506 by wiper 513, and this relay, upon energizing, removes the short-circuit from the impulsing contact 523 at armature 520, prepares a locking circuit for stop relay 505, at armature 521, and at armature 522 connects ground to conductor 426, thus completing a circuit for the stepping magnet 402 of sequence switch S' . Magnet 402 is accordingly energized, but without affecting the position of its wipers, which like the wipers of the sending switch are advanced when the magnet retracts its armature. The second time the circuit of relay 507 is closed by interrupter I, the said relay closes the circuit of the stepping magnet 515 as before and also, since relay 506 is now energized, it momentarily opens the circuit of relay 27 of the trunk relay equipment D at impulsing contact 523. When the circuit of relay 27 is broken, it in turn deenergizes and momentarily opens the circuit of line relay 107 of the first selector E'. When the circuit of relay 507 is broken by the interrupter, it deenergizes and breaks the circuit of the stepping magnet 515, which retracts its armature and advances its wipers 513 and 514 one more step, thus bringing the stop wiper 514 into engagement with the No. 1 contact in its bank. It will be seen that the sending switch S is caused to make an initial or false step before it actually begins transmitting impulses, and this, it may be stated,

is done in order to insure that the first impulse transmitted will be of the standard length.

- The energizations and deenergizations of relay 507 continue in quick succession under control of the interrupter I. After the second deenergization, which terminates the first impulse or interruption of the control circuit, the stop wiper 514 is advanced into engagement with its No. 1 contact, as stated, after the third deenergization wiper 514 is advanced into engagement with its No. 2 contact, and so on, until finally after the sixth interruption has been produced, the stop wiper is advanced into engagement with the No. 6 contact. Since, the first digit in the interoffice code is 6, the required number of impulses have now been transmitted to the first selector E' by means of the relay 27 of the trunk relay equipment D. As previously explained, the No. 6 contact in the lower bank of the sending switch is grounded at this time, and when the stop wiper 514 comes into engagement with this contact, a circuit is completed for the stop relay 505. Upon energizing, the stop relay closes a locking circuit for itself at armature 517, at armature 519 opens the circuit of the impulsing relay 507 in order to prevent the transmission of any more impulses, and at armature 516 completes an automatic rotary circuit for the stepping magnet 515 by connecting wiper 513 with the said magnet through its interrupter contact. On the closure of this automatic rotary circuit, the stepping magnet 515 operates as a buzzer and advances the wipers of the sending switch to normal position.
- As a further result of the energization of the stop relay 505, the circuit of the stepping magnet 402 of the sequence switch S' is broken at armature 518, and the said magnet is deenergized, thus advancing the sequence switch wipers to second position. As a result of the movement of sequence switch wiper 404 from first to second position, ground is removed from the No. 6 contact in the bank of the stop wiper 514 and is connected to the No. 3 contact, the new circuit being traceable from the grounded starting conductor 400 by way of wiper 404 in second position, conductor 412, wiper 307 of register switch J and the contact engaged by said wiper, terminal 332, a jumper connecting this terminal with bus-bar No. 3, and conductor 365 to the No. 3 contact in the bank of the stop wiper. The movement of the other sequence switch wipers is without particular effect at this time.
- The operation of the first selector E', Fig. 1, in response to the first series of code impulses may now be briefly explained. As described in the foregoing, the circuit of the line relay 107 of selector E' is interrupted six times at the armature 26 of relay 27
- of the trunk relay equipment D, the circuit of the latter relay having been interrupted six times at the impulsing contact 523 in the sending switch S. As a result of the six interruptions, the line relay 107 will cause six impulses of current to be transmitted to the vertical magnets (not shown) which operate to raise the wipers 114, 115, and 116 step by step until they arrive at the sixth level of bank contacts. At the end of the vertical movement of the switch, the well-known hunting operation takes place. When an idle trunk is reached, which it will be assumed is the one indicated in the drawing, the test wiper 115 fails to find ground on the test contact 111 and the rotary movement of the switch is arrested. Switching relay 137 is now energized in the usual manner, places ground on the test wiper 115 in order to make the selected trunk busy, and extends the trunk conductors 104 and 106 by way of armatures 135 and 136, wipers 114 and 116, bank contacts 110 and 113, to the trunk conductors 137 and 139. Trunk conductors 137, 138, and 139, it may be stated, extend to and terminate in the second selector E², the circuits of which are not shown, but which is shown diagrammatically in Fig. 6. On the extension of the trunk to the second selector E², the line and release relays of this switch are energized in the usual manner, the switch is prepared for its vertical operation, and a ground is placed upon the release trunk conductor 138.
- Returning now to the sending switch S, when the switch reaches its normal position after the transmission of the first series of code impulses, wiper 513 will engage an ungrounded contact and the circuit of relay 506 will be broken. On deenergizing, relay 506 again closes the shunt around the impulsing contact 523 at armature 520, and at armature 521 breaks the locking circuit of the stop relay 505. The latter relay, on deenergizing, again closes the circuit of the impulsing relay 507 at armature 519 and the transmission of the second series of code impulses is started. As indicated in the drawing, relays 505 and 506 are made slow-acting in order to introduce a brief time interval between the transmission of successive series of impulses, thus giving the selector switches time for their automatic trunk hunting operations. The second series of code impulses is now transmitted similar to the manner in which the first series was transmitted. When the circuit of the impulsing relay 507 is completed at armature 519 by the deenergization of stop relay 505, the said impulsing relay begins to operate intermittently under the control of the interrupter I, and advances the sending switch step by step through the medium of the stepping magnet 515. At the first step of the

switch, relay 506 is energized, removes the shunt from the impulsing contact 523 at armature 520, prepares a locking circuit for the stop relay at armature 521, and closes the circuit of the sequence switch magnet 402 at armature 522. On the second energization of the impulsing relay 507 and on the succeeding energizations thereof, impulses will be transmitted over the switch control circuit comprising conductors 173 and 33 in the manner described in the foregoing, and by the time the stop wiper 514 arrives at the No. 3 contact in its bank, a series of three impulses will have been transmitted. The No. 3 contact in the bank of the stop wiper 514 is now grounded and, accordingly, the stop relay 505 is again energized, a locking circuit being established at armature 517 as before. Relay 505 also breaks the circuit of impulsing relay 507 at armature 519, closes the automatic rotary circuit at armature 516, and at armature 518 breaks the circuit of the sequence switch magnet 402. On deenergizing, the sequence switch magnet advances the wipers to third position, whereupon ground is removed from the No. 3 contact in the bank of the stop wiper 514.

Since there are only two series of impulses in the office code, the sequence switch S' must now be advanced automatically through its third and fourth positions in order to prepare the circuits for the transmission of the thousands digit as soon as the sending switch S has restored to normal. This is accomplished automatically due to the fact that that terminal 331 is cross-connected to bus-bar Y at the I. D. F. instead of to any of the bus-bars which are associated with the bank of the sending switch. When the sequence switch wiper 404 arrives in third position, a circuit is completed for the stepping magnet 402 which extends from the grounded conductor 400 by way of wiper 404 in third position, conductor 413, wiper 308 of register switch J and the contact engaged thereby, terminal 331, a jumper connecting this terminal with bus-bar Y, conductor 371, wiper 403 in third position, and through the interrupter contact and the winding of stepping magnet 402 to battery. Upon the closure of the foregoing circuit, the stepping magnet 402 is energized momentarily and the sequence switch wipers are advanced to fourth position, whereupon a similar circuit is immediately completed which extends from the grounded conductor 400 by way of wiper 404 in fourth position, conductor 414, wiper 309 of register switch J and the contact engaged thereby, terminal 330, a jumper connecting this terminal with bus-bar X, conductor 370, wiper 403 in fourth position, and through the interrupter contact and the winding of the stepping magnet 402 to battery. Upon

the closure of the foregoing circuit, the stepping magnet 402 is energized momentarily and the sequence switch wipers are advanced to fifth or thousands position.

The two series of code impulses have now been transmitted and the director is in readiness to start the transmission of the impulses which correspond to the registered digits. In order that the progress of the call may be kept in mind, it may be stated that in response to the second series of impulses, the wipers of the selector E², Fig. 6, are raised to the third level, whereupon a trunk line is selected extending to the Sunnyside office, the trunk taken for use being assumed to be the one which extends by way of the repeater R to the selector E³. The repeater R is of the standard type and includes means such as a repeating coil by means of which the trunk is divided into two inductively connected sections. It includes also a line relay operated over the incoming section to repeat impulses into the outgoing section, and a slow-acting release relay for grounding the extended release trunk conductor 138.

When the sequence switch S' is automatically advanced to the fifth or thousands position, wiper 404 places ground on the wiper 244 of the thousands register M', and wiper 405 leaves the multiplied contacts which are connected with the grounded conductor 400 and engages its No. 5 contact to which is connected conductor 421 coming from the thousands register switch. As a result of the latter circuit change, when the sending switch S returns to normal after having transmitted the last series of code impulses, the transmission of the series of impulses which corresponds to the thousands digit of the number is not started unless this digit has been registered, for unless the register switch M' has completed its operation, there will be no ground on conductor 421. In the present case let it be assumed that the calling subscriber has completed the dialling of the thousands digit before the sending switch has completed the transmission of the series of code impulses. When the sending switch S arrives in normal position after the transmission of the final series of code impulses, the deenergization of the stop relay 505 will be effective to again close the circuit of the impulsing relay 507. Since, the thousands digit in the number is digit 2, the wiper 244 of the thousands register M' is now standing on the second contact in its bank, and since the wiper 244 is now grounded by way of the wiper 404 of the sequence switch S', there will be ground on the No. 2 contact in the bank of the stop wiper 514. It follows that in the next operation of the sending switch S, two interruptions will be produced in the impulsing circuit, similar to the manner in which the several series of

code interruptions were produced. These interruptions or impulses, relayed by relay 27, are received at the repeater R, Fig. 6, and are repeated over the interoffice trunk line to the incoming selector E³ in the Sunnyside office, which operates to raise its wipers opposite the second level, whereupon an idle trunk is selected extending to a fourth selector which we will assume is the 10 selector E⁵.

During the operation of the sending switch in transmitting the thousands digit of the number, the stepping magnet 402 of the sequence switch S' is energized and deenergized in the usual manner and advances the sequence switch wipers to the sixth or hundreds position. The movement of sequence switch wiper 404 disconnects ground from the wiper 244 of the thousands register M' 20 and connects ground to the wiper 245 of the hundreds register M² by way of conductor 416. Assuming that the calling subscriber has already dialled the hundreds digit 3, the conductor 422 will now have a ground on it, 25 causing the sending switch to restart immediately when the stop relay 505 falls back. Since, the hundreds digit in the number is the digit 3, there will now be a ground on the No. 3 contact in the bank of the stop wiper 514 by way of the wiper 245 of the 30 hundreds register, and the sending switch will operate to transmit a series of three impulses. These impulses, relayed by relay 27, are repeated by the repeater R, Fig. 6, to the fourth selector E⁵ in the Sunnyside office which raises its wipers to the third level and selects an idle trunk extending to a connector switch, which we will assume to be the connector H'.

40 During the operation of the sending switch in transmitting the hundreds digit in the number, the sequence switch magnet 402 is energized and deenergized in the usual manner in order to advance the sequence switch wipers to the seventh or tens position. Assuming now that the calling subscriber has completed the dialling of the tens digit, conductor 423 will be grounded and wiper 246 will be standing on the No. 50 4 contact in its bank, thus extending a ground to the No. 4 contact in the bank of the sending switch S'. A series of four impulses is accordingly transmitted by the sending switch, these impulses, relayed by relay 27, are repeated by the repeater R to the connector H in the Sunnyside office, which, accordingly, raises its wipers in the well-known manner to the fourth level of bank contacts. The sequence switch magnet 402 is energized and deenergized in the usual manner during the transmission of the impulses corresponding to the tens digit, and advances the sequence switch wipers to the eighth or units position with the result 60 that wiper 404 places a ground on wiper

247 of the units register M⁴. Assuming that the final digit has been dialled by the calling subscriber, conductor 424 will now be grounded, the sending switch S will be started on its final operation, and since wiper 247 is in engagement with the No. 5 contact in its bank, a series of five impulses will be transmitted. The last series of impulses, relayed by relay 27, is repeated by the repeater R to the connector H' which is 70 operated in the usual manner to rotate its wipers into connection with the line extending to station A'. Upon completion of the connection to the called line, a signalling circuit is established in the connector in the usual manner and the bell of the called station is operated to notify the subscriber that he is wanted. In the foregoing explanation it has been assumed each time that when the sending switch arrives at normal position after the transmission of a digit, the calling subscriber has already completed the dialling and registration of the next succeeding digit. It will be understood, of course, that in case there is any delay on the part of the calling subscriber, the sending switch will eventually catch up with him and that in such a case, the restarting of the sending switch will be postponed until another digit has been registered. 85

The energization and deenergization of the sequence switch magnet 402 during the transmission of the final series of impulses causes the sequence switch wipers to be advanced to the ninth or switching position, whereupon the following circuit is established for the switching relay 512: from ground by way of sequence switch wiper 406 in switching position, conductor 420, contacts controlled by armature 539, and the lower winding of relay 512 to battery. On energizing, relay 512 establishes a locking circuit for itself at armature 539, breaking its initial energizing circuit at the same time, opens the circuit of relay 507 and armature 540, and at armature 538 disconnects conductor 173 from conductor 202 and connects the former to ground. This latter operation completes a circuit for the switching relay 19 of the trunk relay group D as follows: from ground by way of armature 538, conductor 173, bank contact 170, Fig. 1, wiper 166, working contact of armature 160 and the said armature, armature 24 and its working contact, and the winding of the switching relay 19 to battery. Upon energizing, relay 19 forms a locking circuit for itself at armature 18, connects the trunk conductors 13 and 15 with conductors 50 and 53, respectively, at armatures 16 and 22, and disconnects the said trunk conductors 13 and 15 from conductors 8 and 9, respectively, at armatures 17 and 21. A special adjustment of the contact springs of relay 19 is essential in order to secure a quiet 130

switching through operation. The relay should be so adjusted that the springs represented by armature levers 16 and 22 engage their working contacts before any 5 break contacts are operated, as a result of which the calling subscriber's line will be connected to the line relay of the repeater R in multiple with the relay 23 of trunk relay equipment D. The resistance 6 prevents the short-circuiting of the subscriber's 10 line and the objectionable noise in the receiver which would occur if short-circuiting should take place. Following the engagement of the above mentioned springs, the 15 adjustment is such that armatures 17 and 21 will operate to remove relay 23 from the trunk, after which the complete operation of armatures 16 and 22 will result in the removal of the resistance 6 from across the 20 trunk. The trunk is now clear of all bridges at the trunk relay equipment D. The operation of armature 20 results in the extension of the grounded release trunk conductor 51 to conductor 14 in order that the 25 preceding switches may be maintained in an operated position after the deenergization of the line relay 150 of the director selecting line switch C³.

When the line relay 23 is disconnected from the trunk by the operation of switching relay 19, it deenergizes and breaks the 30 circuit of the slow-acting line relay 150 of switch C³, which deenergizes in turn and opens the circuit of the switching relay 157. Relay 157, upon deenergizing, dissociates the director selecting line switch C³ and the director, notwithstanding the fact that the 35 associated wipers are still standing on bank terminals 168 to 171, inclusive. The breaking of the contact at armature 159 causes the deenergization of relay 27 of the relay trunk equipment D, this is without effect, however, as the bridge has already been removed from the trunk by the operation of relay 19. A 40 further result of the deenergization of relay 157 is to disconnect ground from conductor 173 and from holding conductor 172, as a result of which relays 510 and 511 in the director will deenergize. On deenergizing, relay 511 connects ground to the upper bank 45 of the sequence switch at its armatures 533 in order to advance the sequence switch wipers to their normal position. At the same time, at the upper armature 533 the locking circuit of switching relay 512 is 50 broken and this relay is permitted to deenergize. At armature 532, relay 511 connects wiper 513 of the sending switch S with the stepping magnet 515 through its 55 interrupter contact. This operation, however, is of no particular importance, ordinarily, owing to the fact that the sending switch is restored automatically by the completion of the same circuit at armature 516 of the stop relay. Relay 510, on deenergizing, connects

ground to release conductor 204 at armature 530, thus completing parallel energizing circuits for the release magnet 211 of the master digit controller M, the release magnet 305 of the register switch J, and the 70 release magnets 220, 221, 222, and 223 of registers M' to M⁴, inclusive. The several switches mentioned are accordingly restored to normal position in the well-known manner, each switch opening the circuit of its 75 associated release magnet at its off-normal springs as soon as it is fully restored. The low resistance relay 508 is included in series with conductor 204, and, on energizing, disconnects the holding conductor 172 from the 80 local holding conductor 203 and connects the former conductor to ground. This operation places a ground on the test contact 171 and its multiples in the banks of the director selecting line switches such as the switch C³, and prevents seizure of the director while the register switches thereof are returning to normal position. Relay 510, on deenergizing, also connects up the high 85 resistance relay 509, the upper winding of which is connected to wiper 513 of the sending switch while the lower winding is connected to wiper 403 of the sequence switch. When relay 510 falls back, therefore, relay 509 will be energized, since the sequence switch S' and possibly also the sending switch S are out of normal position, and at armature 527 will prepare a ground for the holding conductor 172. It follows that 90 when the relay 508 falls back on the complete restoration of all the register switches, if the sending and sequence switches are not yet fully restored, the conductor 172 will remain grounded. It may be stated that 95 ordinarily the sending and sequence switches will arrive at normal position at approximately the same time as the register switches are restored, and the relay 509 is provided chiefly to guard against some defect in these switches by which they might be prevented from restoring at all. If one of these 100 switches should get out of adjustment, for instance, and fail to restore, it would render the director completely inoperative, but in such a case relay 509 would be maintained 105 energized in order to keep the trunk extending to the director in busy condition. When either relay 508 or 509 is energized, a ground is placed on conductor 498 which may be 110 used to operate some kind of alarm to signal a switchboard attendant.

The contact springs represented by armature 532 and its resting contact are added to relay 511 in order to insure that the sending switch S will be advanced to normal position 115 in case the calling subscriber should hang up his receiver while the sending switch is operating, and before the stop relay 505 is energized. For example, if the calling subscriber should hang up while the director 120

is in use, the line relay 23 of the trunk relay equipment D will fall back and cause the dissociation of the director selecting line switch C³ and the director, whereupon all the 5 register switches in the director will be restored to normal. If the circuit of the impulsive relay 507 should be broken by the removal of ground from a conductor such as 400 or 421 while the said impulsive relay is 10 operating to transmit impulses before the stop relay 505 is energized, the movement of the sending switch would be stopped and it would remain in an off-normal position. However, the provision of the contact springs 15 mentioned prevents such an occurrence, for whenever the director is released, relay 511 is deenergized and the said contact springs are effective to connect the wiper 513 to the stepping magnet 515, with the result that the 20 sending switch S is always advanced to normal position no matter whether the calling subscriber hangs up prematurely or not.

As described in the foregoing, the connection is switched through and the director is released as soon as the final series of impulses 25 has been transmitted. The director is thus used only during the actual setting up of the connection and is rendered accessible to other subscribers as soon as the connection is completed. After the connection has been 30 switched through, it is the same in all essential particulars as any ordinary automatic connection, such as is found in ordinary automatic telephone systems which do not 35 employ directors and is controlled by the calling subscriber in the usual way. When the called subscriber answers, the calling and called parties will converse as desired, and will replace their receivers when the conversation is finished. The release of the 40 connection is controlled by the calling subscriber. When the receiver is replaced at the calling station, the line and release relays of the repeater R are deenergized, with the 45 result that the holding circuit for the automatic switches in the originating exchange is broken, and with the further result that the control circuit extending over the inter-office trunk to the Sunnyside office is broken also. It follows that all of the automatic 50 switches involved in the connection are restored to normal according to well-known practice.

Having explained the process of setting up and releasing a typical connection, it 55 will be desirable now to consider the special case represented by a connection to a called substation located within the same office as the calling substation. For this purpose, it 60 will be assumed that the subscriber at station A desires to extend a connection to the subscriber at station A², whose telephone number is BRYant 2375. To proceed with the establishment of the connection, when the calling subscriber removes his receiver, his line 65

is extended to a first selector trunk as previously pointed out, and it will be assumed that the first selector trunk illustrated in Fig. 1 is the one taken for use, it being also assumed that the director taken for use is 70 the one illustrated in the drawings. The calling subscriber will now dial the letters B and R of the called number, as a result of which the register equipment in the director operates to register the above letters in precisely the same manner as was described in the preceding case. The register switch J, Fig. 4, is controlled by the line relay 23 of the trunk relay equipment D and receives two series of impulses, one comprising three 75 impulses and the other comprising two impulses, in accordance with which its wipers are raised three steps to the third level, and are then rotated two steps into engagement with the second set of contacts. At 80 the end of the rotary movement of switch J, relays 207 and 208, Fig. 2, deenergize an instant apart and thus cooperate in transmitting an impulse of current to the stepping magnet 212 of the master digit controller M, the wipers of which accordingly advance from second to third position. As a result of the above action, a ground is placed on starting conductor 400 by wiper 219, and a circuit may be traced from the grounded conductor 400 by way of wiper 404, conductor 411, wiper 306, of register switch J and the contact now engaged thereby, terminal 341 on the left-hand side of the I. D. F., a jumper connecting this terminal with bus-bar SW, and thence by way of conductor 564, through the upper winding of 85 relay 512 to battery. On energizing, relay 512 establishes a locking circuit for its lower winding at armature 539.

When the relay 512 becomes energized, a number of circuit changes are brought about, for convenience of explanation the circuit established at armature 537 will first be considered. In this connection, a circuit is 90 traceable from grounded conductor 564, working contact and armature 537, conductor 175, bank contact 168, wiper 164, working contact and armature 158, conductor 52, armature 63 and resting contact, resting contact and armature 66, through stepping magnet 68 to battery. The stepping magnet 68 will energize over the above traced circuit, but will not cause a movement of the wipers 75, 76, and 77. The stepping magnet, upon energizing, opens the circuit of switching relay 57 at armature 67, whereupon the switching relay deenergizes and again connects the slow-acting line relay 61 95 and ground to the trunk conductors 50 and 53, at armatures 54 and 49, respectively. Line relay 61 immediately energizes and places ground upon the release trunk conductor 51 by way of armatures 59 and 46. A further result of the deenergization of 100

relay 57 is the closing of a circuit traceable from grounded conductor 52, resting contact and armature 58, resting contact and armature 65, winding of switching relay 62 to battery. Relay 62, upon energizing, forms a locking circuit for itself by way of armatures 65, 60, and 59, breaks its initial energizing circuit at the same time, and disconnects the trunk conductors 49, 48, and 47 from the primary wipers 75, 76, and 77, and connects them to the secondary wipers 117, 118, and 119, respectively, at armatures 69, 70, and 71. The line relay 61, upon energizing, removes the grounded conductor 52 from the stepping magnet 68, thereby causing it to advance all the wipers one step, the wipers 117, 118, and 119 now engaging bank contacts 120, 121, and 122 respectively. The line relay 61 also closes a circuit for the switching relay 57 in series with the stepping magnet 68 at armatures 60 and 59, and at armatures 64 connects the test wiper 118 to the above circuit at a point between the winding of the switching relay and the winding of the stepping magnet. If the local third selector trunk with which the secondary wipers 117, 118, and 119 of the switch C^4 are now associated is busy, there will be a ground on the test contact with which the test wiper 118 is in engagement, the switching relay 57 will be short-circuited, and the stepping magnet 68 will be operated to advance the switch wipers into engagement with the next trunk line. If the next trunk line is busy, the same operation will be repeated and the stepping magnet 68 will continue to operate in the manner of a buzzer to advance the switch wipers step-by-step until an idle trunk line is encountered. However, if the trunk line with which the wipers of the line switch are associated is idle, there will be no ground potential on the test contact engaged by the test wiper 118, and the switching relay 57 will not be short-circuited, but will be immediately energized in series with the stepping magnet 68, the said magnet remaining inoperative due to the high resistance of the switching relay. Assuming that when the line relay is energized in the present case the local third selector E^6 is idle, then switching relay 57 will be immediately operated when its circuit is completed by the said line relay, as pointed out under the second alternative above. Upon attracting its armature 56, relay 57 connects ground to the test wiper 118, and thus makes the trunk line extending to selector E^6 busy. In addition to the foregoing, at armatures 54, 55, and 49 conductors 50, 51, and 53 are extended by way of armatures 69, 70, and 71 to wipers 117, 118, and 119, respectively, and thence by way of bank contacts 120, 121, and 122 to conductors 123, 124, and 125, respectively, which extend to selector E^6 . When the trunk is extended to the line relay 126 of selector E^6 , the said relay is energized and in turn closes the circuit of the release relay 127. Upon energizing, relay 127 connects ground to the release trunk conductor 124 at armature 128, thereby closing a holding circuit for the switching line switch C^4 , which extends by way of the said conductor 124, test contact 121, wiper 118, armature 70 and its working contact, armature 56 and its working contact, winding of the switching relay 57, and the winding of the stepping magnet 68 to battery. A branch of the above circuit is traceable from armature 56 and its working contact, working contact and armature 65, winding of relay 62 to battery. This holding circuit is established before the slow-acting line relay 61 has had time to deenergize, and is effective to hold the line switch C^4 in an operated position throughout the connection. Relay 61, upon deenergizing, does not again close the circuit of the stepping magnet 68 because of the open circuit at armature 66.

A further result of the energization of the switching relay 62 is the opening of the circuit of the line relay 107 of the first selector E' , with the result that this switch again becomes available for use in setting up other connections.

Returning to a further consideration of the switching relay 512; it may be said that the switching relay 19 in the trunk relay equipment D is operated as previously explained, the calling line switched through, and the director released in the usual manner. In actual practice, it is very likely that the switching through by relay 19 will take place before the trunk is extended to an idle third selector, this introduces no complications, however, as the switch C^4 maintains a ground upon the release trunk conductor 51 until such time as a holding ground is returned from the first selector.

Since the connection has been switched through, it is now the same in all essential particulars as any ordinary automatic connection, such as is found in ordinary automatic telephone systems which do not employ directors, and is controlled by the calling subscriber in the usual way. Assuming that the calling subscriber now dials the thousands digit 2; two interruptions will be produced in the line circuit as a result of which the local third selector E^6 will operate to raise its wipers opposite the second level, whereupon an idle trunk is selected extending to a fourth selector which we will assume is the selector E^7 . Assuming that the calling subscriber now dials the hundreds digit 3; three interruptions will be produced in the line circuit as a result of which the fourth selector E^7 will operate to raise its wipers opposite the third level, whereupon an idle trunk is selected extend-

ing to a connector which we will assume is the connector H^2 . Assuming that the calling subscriber now dials the tens digit 7; seven interruptions will be produced in the line circuit as a result of which the connector H^2 will operate to raise its wipers opposite the seventh level. Assuming that the calling subscriber now dials the units digit 5; five interruptions will be produced in the line circuit as a result of which the connector H^2 will operate to rotate its wipers into connection with the line extending to the station A². Upon the completion of the connection to the called line, a signalling circuit is established in the connector in the usual manner and the bell at the called station is operated to notify the subscriber that he is wanted.

As described in the foregoing, the connection is switched through to a local third selector and the director released as soon as that critical character is dialled, which determines that the connection being set up is for a station in the same office as the calling station. The director and the first selector are used only during the registration of the letters of the called number, and are rendered accessible to other subscribers as soon as the connection is switched through. When the called subscriber answers, the calling and called parties will converse as desired, and will replace their receivers when the conversation is finished. The release of the connection is controlled by the calling subscriber. When the receiver is replaced at the calling substation, the line and release relays of the connector H^2 are deenergized, with the result that the holding circuit for the automatic switches is broken. It follows that all of the automatic switches involved in the connection are restored to normal according to well-known practice.

The object and scope of the invention having been described, what is considered to be new and what it is desired to have protected by Letters Patent will be pointed out more specifically in the appended claims.

1. In a multi-office telephone system, a local office and a plurality of other offices, directors in the local office for registering the digits in called telephone numbers and for controlling automatic switches in accordance therewith, means for associating an idle director with a calling line, and means effective in case the called line is in the local office for immediately restoring the director to common use as soon as sufficient digits are registered to determine the destination of the call.

2. In a multi-office telephone system, a local office and a plurality of other offices, directors in the local office for registering the digits in called telephone numbers and for controlling automatic switches in accordance therewith, automatic switches in

the said other offices controlled from said local office only through the medium of said directors, and automatic switches in said local office directly controlled directly by calling subscribers therein without the intervention of the directors.

3. In a multi-office telephone system, an office selector, a local selector, a divided trunk having two branches extending to said selectors, respectively, the branch extending to said office selector being normally connected, means for connecting a calling line with said trunk line, a director and means for associating it with said trunk line responsive to the call, said director comprising registering devices for recording the digits in the called number, and means responsive to the registration of the office digits in the called number for connecting the local branch and for disconnecting the other branch of said trunk line in case such digits determine that the called party is in the local office.

4. In a multi-office telephone system, office selectors, local selectors, a hunting switch having two seats of wipers for connecting with said office and local selectors, respectively, a trunk line terminating in said hunting switch, means for connecting a calling line with said trunk line, a director and means for associating it with said trunk line responsive to the call, said director comprising registers for recording the digits in the called number, means for automatically operating said hunting switch to extend said trunk line to an idle office selector, and means responsive to the registration of the office digits in the called number for causing said hunting switch to disconnect from the selected office selector and select an idle local selector in case such digits determine that the called party is in the local office.

5. In a telephone system, a trunk line terminating in an automatic switch, means for connecting a calling line to said trunk line, a director and means for connecting it to said trunk line responsive to the call, said director including registering mechanism set by the subscriber on said line, means in the director for operating said switch, and means in said director effective contingent on a particular setting of said registering mechanism for releasing said switch while maintaining the calling line and trunk line connected.

6. In a telephone system, a trunk line terminating in an automatic switch, means for connecting a calling line to said trunk line, a director and means for connecting it to said trunk line responsive to the call, said director including registering mechanism set by the subscriber on said line, second and third trunk lines accessible to said switch, means for operating said switch

to extend said first trunk line to said second trunk line, and means in said director effective contingent on a particular setting of said registering mechanism for releasing said switch and for reoperating the same to connect said first trunk line with said third trunk line.

7. In a telephone system, a trunk line terminating in an automatic switch, said switch having two sets of wipers and a wiper switching relay, means for connecting a calling line to said trunk line, a director and means for connecting it to said trunk line responsive to the call, registering mechanism in said director set by the calling subscriber, means for operating said switch to extend the trunk line via one set of wipers, and means responsive to a particular setting of said registering mechanism for releasing and reoperating said switch and for energizing said relay to extend the trunk line via the other set of wipers.

8. In a telephone system, a trunk line terminating in an automatic switch, two sets of wipers in said switch, a wiper switching relay, a director and means for connecting it to said trunk line when the same is taken for use, a register and a sender included in said director, a distributing frame, contacts in said register bank connected through said frame to said sender, and another contact in said bank connected through said frame to said relay.

9. In a telephone system, a trunk line terminating in an automatic switch, two sets of wipers in said switch, a wiper switching relay, a director and means for connecting it to said trunk line when the same is taken for use, a multi-digit register in said director, a sender normally controlled by said register to transmit series of impulses over a circuit including the normally connected wipers of said switch, and a circuit for said switching relay controlled by said register responsive to a particular setting thereof.

10. In a telephone system, a trunk line terminating in an automatic switch, two sets of wipers in said switch, a wiper switching relay, a director and means for connecting it to said trunk line when the same is taken for use, registering mechanism in said director, a sender controlled by said registering mechanism to transmit impulses through said switch and one set of wipers thereof, and a circuit for said switching relay completed

responsive to a particular setting of the registering mechanism before any impulses are transmitted by said sender.

11. In a telephone system, a trunk line comprising two normally disconnected sections, means for connecting a calling line with the first section, a director, means responsive to the call for associating said director with said trunk line at the junction of said sections, registering mechanism in said director controlled over the calling line and a portion of said first section, automatic switches, sending mechanism in said director controlled by the registering mechanism to control said switches over a portion of the second section, a circuit closer for uniting said sections, and means responsive to a particular registration by said registering mechanism for actuating said circuit closer instead of said sending mechanism.

12. In a telephone system, a trunk line comprising two normally disconnected sections, means for connecting a calling line with the first section, a director, means responsive to the call for associating said director with said trunk line at the junction of said sections, registering mechanism in said director controlled over the calling line and a portion of said first section, automatic switches, sending mechanism in said director controlled by the registering mechanism to control said switches over a portion of the second section, a circuit closer for uniting said sections, and means responsive to a particular registration by said registering mechanism for operating said circuit closer instead of operating said sending mechanism and for dissociating said director and trunk line.

13. In a telephone system, a calling line leading to a line switch having two sets of wipers each having access to a specific group of switches, the said switch automatically functioning to seize a switch of one group responsive to the initiation of a call on the calling line, and means whereby when a predetermined series of impulses is sent from the calling device the said line switch will unseize and hunt for and seize the first idle switch of the alternative group through the alternative wiper set.

In witness whereof, I hereunto subscribe my name this 14th day of December, A. D., 1922.

MICHAEL SCHWARTZ.
